UNITED STATES PATENT OFFICE.

BENJAMIN R. HOISINGTON, OF MINNEAPOLIS, MINNESOTA.

BOILER.

SPECIFICATION forming part of Letters Patent No. 710,579, dated October 7, 1902.

Application filed February 18, 1902. Serial No. 94,580. (No model.)

To all whom it may concern:

Be it known that I, BENJAMIN R. HOISINGTON, a citizen of the United States, residing at Minneapolis, in the county of Hennepin and State of Minnesota, have invented certain new and useful Improvements in Boilers; and I do hereby declare the following to be a full, clear, and exact description of the invention, such as will enable others skilled in the art to 10 which it appertains to make and use the same.

My present invention is especially directed to the improvement of horizontal boilers; and it consists of the novel devices and combinations of devices hereinafter described, and defined in the claims.

The principal objects of my invention are to effect an economy in fuel by the provision of a boiler of greater generating efficiency, to provide a construction in which there is less danger of burning out and filling up of the flues and the joints of various other passages, and in which the flues and various other passages may be more readily cleaned and repaired. These objects I attain by my invention, the preferred form of which is illustrated in the accompanying drawings, wherein like characters indicate like parts throughout the several views.

Figure 1 is a view, principally in vertical section, but with some parts shown in full and others broken away, illustrating a boiler designed in accordance with my invention. Fig. 2 is a transverse vertical section taken on the line $x^2 x^2$ of Fig. 1, and Fig. 3 is a horizontal section on the line $x^3 x^3$ of Fig. 1.

The numeral 1 indicates the horizontal boiler-section, the numeral 2 the fire-box, and the numeral 3 the flues, of a horizontal boiler of the so-called "locomotive" type or such as used in connection with traction-engines and for various other purposes. The walls of the fire-box are water-jacketed, and the rear water-jacketed wall 2^a thereof is curved rearward from a point above the fuel-inlet passage 4 for an important purpose which will be hereinafter noted. Immediately overlying the fuel-inlet passage 4 and projecting inward or forward is a deflecting-plate 5. The numeral 6 indicates the dead-plate, and the 45 numeral 7 the open grate of the fire-box, both of which are of ordinary construction. In the funnel-like extension 8 from the fuel-in-

let passage 4 is an ordinary gravity-closed door 9.

Overlying the fire-box and projecting rearward from the body of the boiler and from the front water-jacketed wall of the fire-box is a horizontally-extended water-leg 10, which at its sides runs into the vertical water-jackets 11 forward between the sides of the boiler 6^a and the sides of the fire-box. This water-leg 10 inclines gradually as it extends rearward, and at its rear end it terminates forward of the rear water-jacketed wall 2^a of the fire-box, so as to leave a flame-passage 12. A series of closely-positioned water-tubes 13 connect the said water-jacketed wall 2^a with the rear end of the water-leg 10, and thus not only afford communication between the two parts, but assist in tying the said parts together. In 70 the outer wall of the water-jacketed section 2^a are plugs 14, located one in line with each tube 13 and serving when removed to permit a cleaning-tool to be passed through the said tube and down into the water-leg 10, thereby 75 making it possible to always easily clean the said parts. The manhole 15 extends vertically through the water-leg 10. This manhole is normally closed by fire-brick or similar material 16, preferably formed in a single 80 section and supported by lugs 17, riveted or otherwise secured to the lower wall of said water-leg.

Above the water-leg 10 is a combustion-chamber 18, the forward vertical wall of 85 which serves as a flue-sheet for the flues 3, which flue-sheet, it will be noted, stands over the intermediate portion of the fire-box. The combustion-chamber 18 in longitudinal vertical section flares or tapers forward, while at 90 its sides it is parallel and runs into the side water-jackets 11. At its rear end said combustion-chamber 18 opens through a slightly-contracted passage 19 into an expanded upper end section 12^a of the flame-passage 12. 95 A manhole 20, which is normally closed by a door 21, opens through the water-jacketed rear wall of the said chamber 12^a, or, in other words, through the upper portion of the water-jacketed rear wall 2^a. The passages 19 100 and 20 stand in line with each other and in such relation to the flues 3 that a flue-cleaner may be passed therethrough and through any and all of the said flues. This enables the

flues to be cleaned from their rear ends, thereby forcing the sediment or scale forward into the smoke-box. In previous constructions it has been necessary to clean the flues from the 5 smoke-box end of the boiler, thereby forcing the scale or sediment back into the fire-box or combustion-chamber. This latter manner of cleaning the flues is objectionable, for the reason that a great deal of the scale cleaned 10 from the flues will be carried back into the flues by the draft.

22 and 23 indicate the removable boiler-plug, which when removed permits a cleaning-tool to be run through the sides of the 15 boiler and into the water-leg 10 to clean the latter. It is also very important to note that the water-leg 10 at end and highest portion communicates with the top of the boiler through vertical side passages 24, formed adjacent to the neck which affords the contracted passage 19. These passages 24 permit steam which will be generated in this 20 highest portion of the water-leg 10 to find its natural escape upward into the top of the 25 boiler. In prior constructions where this escape of the steam from the highest point of the water-leg has not been permitted great trouble has been caused by the burning out of the section thereof wherein the steam has 30 been caged.

With the arrangement described it is evident that the straw or other fuel upon the dead-plate 6 will not burn to any considerable extent, inasmuch as the draft therethrough 35 is cut off by the said plate and by the overlying deflecting-plate 5. Hence the flames from the fuel upon the live-grate 7 will first be directed upward against the forward portion of the water-leg 10, the lower plate of 40 which serves as a crown-sheet, and will be caused to follow the said water-leg or crown-sheet rearward until it reaches the flame-passage 12. The flames to reach the combustion-chamber 18 must pass through the said 45 passage 12, its expanded upper end 12^a, and the contracted passage 19. As the flames make their upward turn around the rear end of the water-leg 10 they are kept in contact with the curved portion 2^a of the rear wall of 50 the fire-box, which section 2^a, it will be noted, is so curved as to follow the line of natural draft of the said flames. In this way the generation of steam at the point noted is greatly increased. A considerable generation 55 of steam will also take place in the short horizontal tubes 13. These tubes further serve to catch and stop any partly-burned straw which may be carried upward by the draft, and thus keep the said incompletely-burned straw from being carried into the 60 flues.

When the flames enter the combustion-chamber 18, they are permitted to expand and to burn with great intensity, and at the same 65 time they are so diffused and spread out that each flue 3 will receive an approximately even heat therefrom.

It will be further noted that by the arrangement above described the water heated in the water-leg 10 is permitted to circulate in almost all directions. For instance, it may freely circulate in either direction through the tubes 13 or transversely through said water-leg or upward through the vertical passages 24.

What I claim, and desire to secure by Letters Patent of the United States, is as follows:

1. A boiler having a combustion-chamber directly communicating with the flues and overlying the fire-box, a water-leg inclined upwardly and projecting rearward between the fire-box and combustion-chamber but terminating short of the rear walls of the fire-box to afford a flame-passage from said fire-box to said combustion-chamber, and further provided with escape-passages leading from the highest point or upper end of said water-leg both laterally and vertically into the body of the boiler and permitting the escape of steam from the water-leg without backing up the water therein.

2. In a boiler, the combination with the fire-box and the flues, of the water-leg 10 projecting rearward over said fire-box and terminating short of the rear wall thereof to afford the flame-passage 12 expanded at 12^a, and the combustion-chamber 18 overlying said water-leg 10 and communicating with the expanded end 12^a of said flame-passage, through the contracted neck or opening 19, the forward wall of said chamber 18 serving as a flue-sheet to which the flues connect, substantially as described.

3. In a boiler, the combination with the fire-box 2, the overlying and forwardly-flaring combustion-chamber 18 to the front plate of which the flues connect, the rearwardly-projecting and upwardly-inclined water-leg 10 extending between said fire-box and combustion-chamber, the flame-passage 12 extending between the rear ends of said water-leg and the rear wall of said fire-box and terminating in the expanded chamber 12^a, the manhole 20 opening into said section 12^a through the rear end of the boiler, the contracted passage 19 affording communication between said chambers 12^a and 18, and the circulating-passages 24 extending from the rear end of said water-leg, around said contracted passage 19 and leading to the upper portion of the boiler, substantially as described.

4. In a horizontal boiler, the combination with a fire-box having a fuel-passage in its rear end and a deflecting-plate projecting inward from the rear wall of the fire-box above said fuel-passage, of a water-leg projecting rearward over the fire-box and terminating above said deflecting-plate but leaving a flame-passage between the same and the rear wall of the fire-box, and a combustion-chamber leading forward from said flame-passage, overlying said water-leg, and directly communicating with the flues.

5. A boiler having a water-jacketed rear

wall, a rearwardly-projecting water-leg overlying the fire-box but terminating short of the rear wall thereof to afford a flame-passage, a plurality of horizontal tubes connecting the

5 inner end of said water-leg to the said water-jacketed rear wall and crossing said flame-passage, and a combustion-chamber overlying said water-leg and communicating with said flame-passage and with the flues, substantially as described.

6. In a horizontal boiler, the combination with a fire-box having a water-jacketed rear wall and a fuel-passage opening therethrough, of a deflecting-plate projecting inward above 15 the same, a water-leg projecting rearward and terminating above said deflecting-plate but leaving a flame-passage at the rear thereof, a plurality of horizontal tubes crossing said flame-passage and affording communication 20 between the rear end of said water-leg and the water-jacketed rear wall of said fire-box,

and a combustion-chamber overlying said water-leg and communicating with said flame-passage and with the flues, substantially as described.

25

7. A boiler provided with the fire-box 2, with fuel-inlet passage 4 deflecting-plate 5 and water-jacketed rear wall curved rearward and upward at 2°, in combination with the rearwardly-projecting water-leg 10 overlying 30 the fire-box and terminating short of said wall-section 2^a to afford the curved flame-passage 12 expanded at 12^a, and the combustion-chamber 18 communicating with the flues and with the expanded chamber 12^a of said flame-passage substantially as described.

In testimony whereof I affix my signature in presence of two witnesses.
